CLAIM

The ornamental design for a stand for hair clipper machine, as shown and described.

DESCRIPTION

FIG. 1 shows a side view of the stand for hair clipper machine. FIG. 2 shows a plan view thereof.

FIG. 3 shows another side view thereof.

FIG. 4 shows an end view thereof; and,

FIG. 5 shows another end view thereof.

The broken lines in the figures are for illustrative purposes only and form no part of the claimed design.
